MOSES CALVERT, OF MARSHALL, OHIO.

Letters Patent No. 79,103, dated June 23, 1868.

IMPROVEMENT IN CHURNS.

The Schedule referred to in these Letters Patent and making part of the same.

TO ALL WHOM IT MAY CONCERN:

Be it known that I, MOSES CALVERT, of Marshall, county of Highland, and State of Ohio, have invented an "Improved Churn;" and I hereby declare the following to be an exact description thereof, reference being had to the accompanying drawings, and to the letters of reference marked thereon, making a part of this specification, in which—

Figure 1 is a side elevation of the churn, and gearing-devices for operating it.

Figure 2 is a front view of the same.

Figure 3 is an end view of the lower beater.

Figure 4 is a side view of the beaters as attached to the upright lever.

Figure 5 is a top view of the beaters.

The nature of my invention consists in the arrangement and combination of the beaters of the churn, and the manner in which they are operated, with the devices, as located on an upright frame.

A represents an upright frame-piece, attached to the end of a square base, B, and supported by two inclined rods, C C, attached to each side of the frame-piece A and the base, B.

A front frame-piece, D, supported by two braces, E E, above and below, is attached to the upper half of the frame-piece A.

The frame-pieces A and D are the supports for the shafts or journals G and H. On the upper shaft, G, is a small pulley-wheel, I, driven by belt J, that runs on a larger pulley-wheel K, which is operated by a crank, L, at the rear side of the frame.

On one end of the shaft G, at the front side, and near the top of the frame, a balance-wheel, M, is attached, which is connected with the pitman and lever N by the pin O, so as to drive the beaters in the churn P vertically, with a free and accelerated motion. Q is a guide, to maintain the proper position of the lever N.

The lower beaters, R, are formed of two cross-pieces, mortised together, and bevelled to a sharp edge above and below, the ends of each piece having an open slot, S, so as to allow the beaters R to divide and thoroughly break the cream.

A short distance above the lower beaters, R, are two or more square beaters, T T, set crosswise through the upright lever N, with their sharp edges above and below, also for the purpose of assisting in dividing and breaking the cream.

The advantages of this arrangement and combination are the absence of cog-gearing in the working-devices, therefore making no noise whilst in operation; its economy and simplicity of construction, and the facility with which it is operated, by which a small child can, with the greatest ease, do the churning, which is generally a laborious operation.

What I claim as my invention, and desire to secure by Letters Patent, is—

The construction and combination of the frame, gearing, and dasher, when arranged and operating as herein described, and for the purposes set forth.

MOSES CALVERT.
